(57) **CLAIM**

The ornamental design for a sensor fitting, as shown and described.

DESCRIPTION

FIG. 1 is a top and front perspective view of a sensor fitting showing the new design;

FIG. 2 is a right side elevation view thereof, which is the same as the left side elevation view thereof;

FIG. 3 is a front elevation view thereof, which is the same as the back elevation view thereof; and,

FIG. 4 is a top view thereof, which is the same as the bottom view thereof.

The broken line showing of structural features is included for the purpose of illustrating non-claimed subject matter and forms no part of the claimed design.
